UNITED STATES PATENT OFFICE.

HERBERT R. BLISS, OF MONROE, MICHIGAN.

METHOD OF CONSTRUCTING AND SEALING SHIPPING-CASES.

1,379,797.

Specification of Letters Patent.

Patented May 31, 1921.

Application filed January 26, 1920. Serial No. 354,174.

To all whom it may concern:

Be it known that I, HERBERT R. BLISS, a citizen of the United States, residing at Monroe, in the county of Monroe and State 5 of Michigan, have invented certain new and useful Improvements in Methods of Constructing and Sealing Shipping-Cases, of which the following is a specification.

This invention relates to a method of constructing fiber shipping cases and has for its object a fiber shipping case that can be constructed and sealed with a minimum use of fiber board and yet has a maximum strength and a maximum capacity for its dimensions. 10 These features will be more thoroughly amplified after the details have been made known. In the drawings,—

Figure 1 is a plan view of the blank for the side walls.

20 Fig. 2 is a section on the line 2—2 of Fig. 1.

Fig. 3 is a plan view of the blank for each end.

25 Fig. 4 is a perspective showing one of the ends or covers made up.

Fig. 5 is a section on the line 5—5 of Fig. 4.

Fig. 6 is a perspective of the blank made up into the side walls.

30 Fig. 7 is a section on the line 7—7 of Fig. 6.

Fig. 8 is a section showing one of the flaps bent over to the outside preparatory to receiving the end or cover.

35 Fig. 9 shows how the cover is wire-stitched to this flap.

Fig. 10 is a section on the line 10—10 of Fig. 6.

40 Fig. 11 is a perspective of the container before it is sealed and as it is ready to receive its contents.

Fig. 12 is a section on the line 12—12 of Fig. 11.

45 Fig. 13 is a perspective view showing the container with the cover sealed in place.

Fig. 14 is a view showing how the cover is wire-stitched to the rest of the container by a machine for that purpose.

50 Fig. 15 is an enlarged section showing the wire stitch about to be driven into the flange of the cover and the flap of the side wall.

Fig. 16 is a similar view showing how the stitch is finished.

55 Fiber shipping cases have heretofore been usually constructed with overlapping

flanges that form the end walls. Prior to the advent of the machine described in Patent #1,174,943, of which I am one of the joint patentees, the only commercially successful way of sealing these overlapping flaps on the closing end of the container was to use either glue or the paper sealing strip or both. By employing the thin flexible anvil described and claimed in said Patent #1,174,943 it is possible to seal the closing end by wire stitching, which has numerous points of superiority over the previous methods of gluing or pasting the sealing strip thereover.

Another method of constructing and sealing fiber shipping cases is to construct the side walls in the usual way but without any flaps and then use an end wall with a flange like an ordinary shoe box cover, but instead of fitting the flange over the outside of the side walls the cover is inverted and the flange fitted inside the side walls. This enables an anvil to be gotten in behind so that the flange may be wire-stitched to the side walls of the case. This method of construction results in considerable saving of material over the overlapping flap way of sealing a case and runs into very considerable saving in dollars and cents where cases are used in large numbers. On the other hand, it has the disadvantage of lessening the capacity of the box for the given dimensions, it forms a pocket to collect water if left out in the rain, and the boxes are not easily stacked. Furthermore, the projecting rim has to sustain all of the weight of the box and contents and very often breaks and starts the box tearing especially in handling.

It is the object of the present invention to afford a method of constructing and sealing fiber shipping cases which will have all the advantages of economy in box material attending the last form described and which will have the advantages of capacity and even more strength than that afforded by the case that is provided with overlapping flaps.

To construct such a box I slot and crease a piece of fiber board to form the four side walls, as shown in Fig. 1, with the joining flap *a*, which may be turned inside of the side wall at the opposite end of the blank, as is shown in Figs. 6 and 10, and wire-stitched thereto to form the side wall structure of the container. The slots and creases *b* and *c*

c respectively form four narrow cover-attaching flaps *d* for a purpose presently to be described.

In Fig. 3 the blank for each end wall or cover is shown. In Fig. 4 this blank is shown made up into the end wall or one of the end covers. It will be seen that the wings *x* are turned inside of the flanges *e* and wire-stitched thereto. This cover may be fitted 10 over the bottom of the box in the manner shown in Figs. 11 and 12. Any ordinary anvil of the horizontal arm type can be then inserted in the empty box and the flange of the cover stitched to the side walls of the 15 box to form the bottom closure.

However, the top cover cannot be fastened to the container of the ordinary type in this way for there is no way to get an anvil in place to clench the wire stitches. 20 It is due to this reason that the cover has been inverted and inserted within the top opening allowing the anvil to get in on the inside of the rim thus formed. This, as already explained, has disadvantages which 25 have been enumerated.

By forming the side wall blanks with the cover-attaching flap *d*, these cover-attaching flaps may be bent outside, as shown in Figs. 8, 9 and 11. The top cover may then 30 be fitted over the top of the box including the bent-over cover-attaching flaps. A thin blade anvil such as shown in Figs. 15 and 16 and described in my prior Patent #1,174,943 may then be inserted between 35 the bent-back flap and the flange of the cover and staples or wire stitches driven into the flanges and the flaps, as is clearly shown in Figs. 14, 15 and 16. Of course, it will be obvious that other metallic fastening means might be likewise clenched through 40 these overlapping members by the aid of such a thin anvil. In carrying out this method it will be evident that the machine is not a theoretical necessity for with the 45 anvil rigidly supported at one end the method could be carried out by driving the fasteners in by a hammer. On the other hand, it would be obvious that the wire stitching or riveting method could not be 50 carried out without a blade anvil tool.

In the specification I have referred to fiber shipping cases. It will, of course, be evident that the method applies not only to the so-called fiber shipping cases but corrugated board cases, paste-board or any 55 equivalent material.

In Fig. 14 I have shown how the anvil is inserted under the overlapping cover flanges and attached flap. The case is supported upon a work table there shown. As 60 the stitches are driven in and clenched, as shown in Figs. 15 and 16, obviously the case will be shifted along the blade anvil to a position where another stitch is to be taken until a whole line of stitches is taken, as 65 shown in Fig. 13. The case may then be turned on another of its sides and the operation repeated.

What I claim is:

1. The method of constructing and sealing shipping cases of fiber or equivalent material, which comprises the constructing of the side walls and providing them with attaching flaps to parallel the side walls on the outside, the securing of a flanged 75 cover over the end and the attaching flaps, and the passing of metal fastening members through the overlapped flanges and flaps and clenching them against a blade anvil inserted between the flaps and the side 80 wall of the case.

2. The method of constructing and sealing a fiber shipping case, which consists of providing side walls that are united together and which have attaching flaps parallel with the outside of the side walls, the securing of a flanged cover over the end of the box and over the flaps to overlap the flaps, the placing of a blade anvil rigidly supported at one end with its free end between the flap and the side wall, and the driving of metallic fastening members through the overlapping flange and flap at different points therealong and clenching the same against the blade anvil as the case 95 is shifted along the blade anvil.

3. The method of constructing and sealing shipping cases of fiber or equivalent material, which consists in providing side walls properly united and having at their tops 100 attaching flaps paralleling the side walls, the securing of a flanged cover over the end and in overlapped relation with respect to the attaching flaps, the insertion of a blade anvil between the flaps and the side walls, 105 and the driving of a line of successive wire stitches through the overlapped flange and flaps and clenching the same on the said blade anvil.

In testimony whereof I affix my signature. 110

HERBERT R. BLISS.
